CLAIM

The ornamental design for a pet enrichment device as shown and described.

DESCRIPTION

FIG. 1 is a perspective view of a pet enrichment device showing our design;

FIG. 2 is a top view of the pet enrichment device;

FIG. 3 is a front view of the pet enrichment device;

FIG. 4. is a back view of the pet enrichment device;

FIG. 5 is a side view of the pet enrichment device; and,

FIG. 6 is a bottom view of the pet enrichment device. Portions design which are not claimed are shown in dashed lines.
